JACQUARD COVERING AND TUCK PATTERN
DEVICE FOR FLAT HOSIERY FRAMES

Anton Loimann, Chemnitz, Germany

Application May 15, 1934, Serial No. 725,781
In Germany June 8, 1933

2 Claims. (Cl. 66—98)

This invention relates to a jacquard covering and tuck pattern device for flat hosiery frames, in which auxiliary sinkers, vertically adjustable according to pattern, are provided within range of the knocking over bits.

To avoid the defects of the known jacquard covering or tuck pattern devices and to impart to the vertically adjustable auxiliary members a reliable drive during their forward motion in the direction towards the frame or covering needles without being forced to move the guide bed of the auxiliary members, disposed relatively far below the sinker bar, so that the bed can be stationary, though it may be taken out. The invention provides that the auxiliary members are arranged in their guide bed so as to be both vertically and horizontally movable therein. The auxiliary members are adjusted in the direction to the covering or frame needles by a presser bar capable of forward and backward motion, so that the back pressure of the needles is taken up not by the low guide bed of said members, but almost completely by the presser bar, and the guiding of the auxiliary sinkers during vertical adjustment as well as the driving motion are effected in a more reliable manner than in known devices. The arrangement just described affords the considerable advantage that the auxiliary members may safely be adjusted from below through the row of jack and dividing sinkers so high that their upper ends will act on the back of the covering needles for guiding them, in open work, reliably to the frame needles without the least trouble which otherwise easily develops in connection with auxiliary members.

One form of the invention is illustrated in the accompanying drawing, in which Figure 1 is a side view of the parts of an ordinary flat hosiery frame required for understanding the invention and shown in position during regular operation; Fig. 2, a view of the same parts during the production of a covering pattern.

Referring to the drawing, the jack and dividing sinkers *b* are displaceable on the lower part *a* of the sinker bar and cooperate as usual with the needles *c*. Knocking over takes place on the bits *e*. The comblike yet integral presser bar *d* is capable of horizontal forward and backward adjustment. It is supported on the top *t* of the sinker bar. The sinker bar is recessed so that the presser bar *d* with its edge *l* can be withdrawn or retracted into a position back of the ordinary working position and thus the auxiliary members *f* can be adjusted in front of the presser bar.

In ordinary operation the presser bar *d* is hor-

izontally moved to and fro according to the double arrow *x*, so that it comes within range of the needle beards during pressing and the otherwise unavoidable swinging motion of the needles for pressing off can be dispensed with.

In this case the auxiliary members *f* are retracted under the presser edge *l* of the presser bar *d*. For carrying out open work the auxiliary members *f* are movable up and down in stationary guides of the machine frame and rest with their lower end in known manner on the plates *g* guided in the machine frame and connected by threads or wires *h* with a jacquard attachment by means of which they can be horizontally adjusted on their guide bed. The plates *g* possess one or several steps and when displaced raise the auxiliary members *f* from a lower inoperative into a higher operative position. The guide beds of the members *f* and of the plates *g* are stationary, yet removably supported, so that the threads or wires *h* can be connected with plates *g* outside the machine. After removal of the guide bed of the plates *g* the auxiliary members *f* rest with their projecting nibs *r* on an edge of their guiding device *z*.

When the members *f* are used, i. e., patterns are produced, the presser bar *d* is moved far enough away from the needles *c* to allow the members *f* to be adjusted in front of the presser edge *l* and to be pressed forward acting against the beards of the frame needles or against the transfer needles.

To produce lace patterns the members *f* are raised high enough to have their upper ends *k* beyond the lower nibs of the jack and dividing sinkers. During forward motion of the presser bar *d*, driven by a special eccentric, the auxiliary members *f* are pressed against the backs of the transfer needles *m* in a manner similar to the well known rock members of U. S. Patent No. 1,858,777 after the transfer needles have been lowered, so that the transfer points engage the grooves of the frame needles *c* and take up their loops. As the members *f* do not engage the points of the transfer needles *m*, but act on a higher and much stronger part thereof, the transfer points cannot be damaged by the pattern mechanism or, particularly, by the members *f*.

The device described is suited also for producing tuck patterns. For this purpose, those members *f* whose needles are to be pressed off are raised by means of the plates *g* to such an extent that the upper ends of the auxiliary members *f* pass between the lower nibs of the jack and dividing sinkers *b*, whereupon the upper

ends *k* of the raised members *f* are pressed against the respective needle beards by the bar *d*, so that these needles receive the finished loops whereas the loops of the needles whose auxiliary members *f* have not been raised are locked in the needle beards.

It is possible to provide only one step on the plates *g* to raise the operating members *f* for producing both tuck or lace patterns. In this case 10 the upper ends of the members *f* act upon a lower point of the transfer needles than when raised by a special step of the plates *g*.

It is not absolutely necessary to move the presser bar horizontally to and fro, on the contrary, it being possible to move the frame needles 15 with the transfer needles onto the upper ends of the raised members *f*.

Instead of providing a presser bar *d* on the top of the sinker bar there may be arranged a 20 bar moving the auxiliary members *f* to and fro between the jack and dividing sinkers and the

knocking over comb or below the latter. For the same purpose it is possible to use the knocking over comb.

I claim:

1. Jacquard covering and tuck pattern device 5 for flat hosiery frames, comprising knocking for bits, a guide bed, auxiliary members disposed in said bed and vertically and horizontally movable therein, a presser bar capable of forward and backward displacement, and means for 10 raising said auxiliary members from inoperative position to within range of said presser bar, the upper ends of the raised members being moved in a to and fro horizontal direction.

2. A device according to claim 1, in which the 15 upper ends of the auxiliary members after raising the latter act on the backs of the covering needles beyond the lower nibs of the jack and dividing sinkers.

ANTON LOIMANN. 20
